CLAIM

The ornamental design for a blade-blade housing bearing interface for a low friction rotary knife, as shown and described.

DESCRIPTION

FIG. 1 is a top plan view of a blade-blade housing bearing interface for a low friction rotary knife illustrating my ornamental design;

FIG. 2 is a side elevation view thereof;

FIG. 3 is a side elevation section view thereof, illustrating a section defined by section lines 3-3 in FIG. 1; and,

FIG. 4 is a magnified section view thereof, illustrating a section defined by the section lines 4-4 in FIG. 1.
